UNITED STATES PATENT OFFICE.

HOWARD H. OSBORN, OF CHICAGO, ILLINOIS, ASSIGNOR TO H. G. FISCHER & COMPANY, OF CHICAGO, ILLINOIS, A CORPORATION OF ILLINOIS.

SPARK GAP.

Application filed June 10, 1921. Serial No. 476,640.

This invention relates in general to apparatus for generating electric current of high frequency and voltage, and has more particular reference to spark gaps employed in 5 such apparatus, the particular embodiment of the invention to be hereafter described being of that character comprising a part of the electro-therapeutic equipment employed by physicians.

10 A principal object of the invention is the provision of a simplified and highly efficient spark gap dispensing with certain elements of construction heretofore deemed essential, and being susceptible of comparatively inexpensive commercial production.

My invention also contemplates the provision in a device of the character described of parts particularly adapted for the purposes heretofore stated and at the same time 20 serving to muffle the sound and to dim or modify the light resultant from the sparks at the gaps.

A still further object of the invention is the provision of a sparking device having 25 the above characteristics in combination with means for ventilating the cells formed by the multiple gaps, and with means for varying the length of the spark by rendering inoperative one or more individual gaps.

30 Numerous other objects and advantages of the invention will be apparent as it is better understood from the following description, which, taken in connection with the accompanying drawings, discloses a preferred embodiment thereof.

Referring to the drawings:

Figure 1 is a plan view of a multiple spark gap embodying the principles of my invention;

40 Fig. 2 is a longitudinal vertical section through the same;

Fig. 3 is a section taken transversely of the device;

Fig. 4 is a perspective of one of the conductive disks;

Fig. 5 is an enlarged view of the bushing through which the short circuiting rod extends; and

50 Fig. 6 is a perspective of the short circuiting rod.

The embodiment of my invention, shown by way of illustration in the drawings, comprises primarily a pair of end holding plates 11, three glass connecting rods, 12, 13, ex-

tending therebetween, and a series of sparking cells indicated generally by the reference character 14. Upon the end plates 11 are appropriate sockets 15 for the glass connectors 12. In the upper parts of these plates are slots 16 for the reception of screw threaded projections 17 of sockets 18 in which the third glass connector 13 is retained. The material about the lower part of the slots 16 is beveled, and nuts 19 having pointed or beveled noses 21 are provided and adapted to be screwed upon the projections 17 and into the beveled portion of the plate to hold the top connector in place. In this manner the connector 13 is rendered removable in order to permit the taking apart and removal of the several parts of the device.

At opposite ends of the series of sparking cells are disks 22 against which end clamps 23 are pressed by means of screw posts 24 extending through the plates 11, and by means of which the entire series of sparking cells is pressed tightly together and held in place. The screw posts 24, in the present instance, constitute also binding posts with which the wires of the circuit may be connected to include the sparking device therein. The sparking cells are formed by the disks 22 and similar disks 25 arranged in series through the device. The disks 22 are provided with studs 26 secured thereto by means of screws 27 and extending inwardly. Each disk 25 is equipped with oppositely extending studs or units 28 and 29 which are secured together by means of screws 31 extending through apertures 32 in the central portions of the disks, the gaps 33 being provided between the opposed studs or units 26, 28 and 29. The electric current is passed through the binding posts 24, the disks 22 and 25, these being formed of conductive material, and through the studs or units 26, 28 and 29, the sparks occurring at the gaps 33.

Housings or encasing members 34 are provided between the disks 22, 25 and are formed of insulating material in order that the electric current may be directed through the sparking elements hereinbefore described. In the present instance these housings or encasing members are cylindrical in form and composed of glass which is exteriorly ground in order to dim or modify the light from the sparks. It will be seen

that each of these members encloses one 5
sparking gap and that the cells are formed
merely by the use of the conductive disks
and single housings. At the same time acci-
dental short circuiting is prevented, and ac-
curate occurrence of sparking insured by the
use of appropriate insulating material. in
said housings or encasing members.

Extending through the binding posts 24
10 and the end clamps 23 is a passageway 35
through which compressed air from a tube
36 is introduced into the device, and the
disks 22 and 25 are provided with apertures
37 preferably arranged in staggered rela-
15 tion to permit passage of air between the
gaps 33 and through the various cells. The
course of air is thus that indicated by the
arrows, it being introduced through one
binding post and out at the other.

20 The disks are recessed at points 38 where-
by to engage the appropriate connectors 12,
13, and are of such dimension that they en-
gage the other connector 12 at 39 so that
25 said disks are held firmly in place between
the connectors. In order to vary the length
of the spark the disks are provided with
aligned apertures 41 through which a short
circuiting rod 42 having an insulating
30 handle 43 and a split end 44 is adapted to
extend. A bushing 45 is provided upon one
of the plates or disks 22, being adapted to
be positioned thereon by means of a slot 46
appropriately formed to fit upon the edge of
35 the disk. It will be apparent that by in-
serting this rod through a greater or less
number of the disks, any desired number of
them may be short circuited so that spark-
ing will occur only between the units on
40 the other disks. It will be apparent that
with the foregoing construction I have pro-
vided a spark gap of comparatively few

parts, simply arranged, and efficient in oper-
ation.

It is though that the invention and many
of its attendant advantages will be under-
45 stood from the foregoing description, and
it will be apparent that various changes may
be made in the form, construction and ar-
rangement of the parts without departing
from the spirit and scope of the invention or
50 sacrificing all of its material advantages,
the form hereinbefore described being
merely a preferred embodiment thereof.

I claim:

1. An electric spark gap, comprising a 55
series of cells, each composed of spaced disks
of current conducting material provided
with projections extending into the cell in
opposed relationship and a ring of opaque
60 insulating material eccentrically positioned
and extending between said disks and en-
closing said projections to insure sparking
therebetween, means for clamping the disks
and rings of the several cells together to
65 form a unitary apparatus, and current con-
ducting means associated with the disks at
the opposite ends of the apparatus.

2. An electric spark gap, comprising a 70
series of cells, each composed of spaced disks
of current conducting material provided
with projections extending into the cell in
opposed relationship and a ground glass ring
75 eccentrically positioned and extending be-
tween said disks and enclosing said projec-
tions to insure sparking therebetween, means
for clamping the disks and rings of the
several cells together to form a unitary ap-
paratus, and current conducting means asso-
ciated with the disks at the opposite ends of
the apparatus.

HOWARD H. OSBORN.
